(57) **CLAIM**

The ornamental design for a cap, as shown and described.

DESCRIPTION

1. Cap

Cap whose flexible material enables it to be flattened when it is not worn.

1.1 is a bottom plan view of a cap showing our new design;

1.2 is a top plan view thereof;

1.3 is a side elevation view thereof;

1.4 is a side elevation view thereof in a flattened position.
